CLAIM

The ornamental design for an infant changing pad, as shown and described.

DESCRIPTION

FIG. 1 is a front, left-side perspective view of an infant changing pad showing my new design;

FIG. 2 is a front, right-side perspective view thereof;

FIG. 3 is a rear, right-side perspective view thereof;

FIG. 4 is a rear, left-side perspective view thereof;

FIG. 5 is a front elevational view thereof;

FIG. 6 is a rear elevational view thereof;

FIG. 7 is a left-side elevational view thereof;

FIG. 8 is a right-side elevational view thereof;

FIG. 9 is a top plan view thereof;

FIG. 10 is a bottom plan view thereof; and,

FIG. 11 is a front, left-side perspective view of the infant changing pad in an environment of use.

The broken lines shown in the drawings illustrate environment and form no part of the claimed design.

1 Claim, 11 Drawing Sheets
